UNITED STATES PATENT OFFICE

101,482

DESIGN FOR A TUNING DIAL FOR RADIO RECEIVERS

John R. Morgan, Oak Park, Ill., assignor to Sears,
Roebuck and Co., Chicago, Ill., a corporation
of New York

Application June 26, 1936, Serial No. 63,511

Term of patent 7 years

To all whom it may concern:

Be it known that I, John R. Morgan, a citizen
of the Republic of Guatemala, residing at Oak
Park, in the county of Cook and State of Illinois,
have invented a new, original, and ornamental
Design for a Tuning Dial for Radio Receiver, of
which the following is a specification, reference
being had to the accompanying drawing, forming
a part thereof.

Fig. 1 is a front plan view of a tuning dial for
radio receiver embodying my new design.

Fig. 2 is a sectional view taken substantially
along the line 2—2 of Fig. 1.

Fig. 3 is a rear plan view of the same.

I claim:

The ornamental design for a tuning dial for
radio receivers, as shown.

JOHN R. MORGAN.
